Hyman Fidel, Great Neck, N.Y., assignor to Modecraft Company, Inc., New York, N.Y., a corporation of New York

Filed July 28, 1960, Ser. No. 61,552

Term of patent 14 years

(Cl. D15—3)

FIG. 1.

FIG. 2.

Des. 193,183

PAGE 2

FIG. 3.

FIG. 4.

FIG. 1 is a front perspective view of a shampoo chair in retracted position showing my design;

FIG. 2 is a front perspective view showing the ottoman in extended position and head rest removed;

FIG. 3 is a front perspective view of the shampoo chair in fully extended position and showing the head rest removed; and

FIG. 4 is a rear elevational view of the shampoo chair in the condition shown in FIG. 1.

I claim:

The ornamental design for a shampoo chair, substantially as shown.
